UNITED STATES PATENT OFFICE.

ANDREW VALEGGIA, OF LONDON, ENGLAND.

PENCIL-HOLDER.

1,375,029.

Specification of Letters Patent. Patented Apr. 19, 1921.

Application filed December 31, 1919. Serial No. 343,675.

To all whom it may concern:

Be it known that I, ANDREW VALEGGIA, a Swiss citizen of London, England, have invented new and useful Improvements in 5 Pencil-Holders, of which the following is a specification.

This invention relates to pencil-holders having screw-propelled means for advancing the lead, and it has for its object to provide 10 an improved pencil-holder of this kind possessing in addition the characteristics of a magazine pencil-holder, that is to say a pencil-holder adapted to contain several spare leads in addition to that lead which 15 for the time being is in use, and provided with means for enabling such spare leads to be brought into operative position in succession as the lead in use becomes exhausted.

One form of the improved pencil-holder 20 is illustrated in the accompanying drawings, wherein Figure 1 is a side elevation, partly in section on an axial plane, while Figs. 2, 3, 4, and 5 are cross-sections on lines 2—2, 3—3, 4—4, and 5—5 of Fig. 1, respectively, 25 and Fig. 6 is a cross-section (corresponding to Fig. 5) of a similar pencil provided with a magazine for holding more than four leads.

In the example illustrated, the outer casing or barrel comprises two cylindrical main 30 sections, namely, a rear section 11 and a front or magazine section 12, which are united by a screw-joint 13, the magazine-section 12 having a conical point-section 14 attached by a screw-joint 15 so as to be removable for the purpose of affording access 35 to the interior of the magazine. The axial sheath 16, for containing that lead which is in use, extends throughout the length of the 40 magazine-section 12 and is semi-cylindrical except at its ends. The sheath 16 as a whole is rotatable relatively to the barrel; the front end 17 of the sheath being for a short distance wholly cylindrical and fitted to 45 turn in a bearing 18 in the point section 14, while the rear end of the sheath is fixed in an aperture in a cam-disk 19 which is capable of turning in a chamber immediately in rear of an apertured diaphragm 20 forming the rear closure for the magazine-section 12.

The effective internal length of the magazine-section 12 corresponds to the length of a single lead, and its inner wall is formed

with a series (four in the example) of approximately semi-cylindrical, longitudinally-extending magazine-recesses 21 for the reception of spare leads, which rest between the diaphragm 20 and the forwardly-tapering inner surface 22 of the point-section 14; the recesses 21 being spaced apart 60 at equal angular intervals around the axis of the holder. The radial depth of each magazine-recess 21, measured from the axis of the holder, is such that the semi-cylindrical sheath 16 (with its contained lead, if 65 any) will have just sufficient room to revolve in the central space between the spare leads housed within the several magazine-recesses (see Fig. 5).

The axial bore 23 of the point-section 14 is of such diameter as to allow a lead to pass through it friction-tight, and in order to effect the extrusion of that lead which is in use, as it wears away, and also to furnish an abutment for the pressure upon the point of 75 the lead in writing, a screw-propelled plunger 24 is fitted to slide lengthwise of the axial sheath 16. This plunger consists of a rod having a round section of two radii corresponding respectively to the radii of the internal and external surfaces of the semi-cylindrical portion of the sheath 16, so that said sheath together with the plunger presents the form of a complete solid cylinder; 80 an arrangement which insures the plunger 85 and sheath turning as one in either direction about their common longitudinal axis when so required.

The plunger 24, when retracted from 90 within the sheath 16, passes rearward along an axial bore 25 in a screw-barrel 26 which is rotatably mounted within the rear section 11 of the holder; the screw-barrel 26 having at its rear end an axial pindle 27 which, passing through a hole in a diaphragm 28 which 95 forms the rear closure of the section 11, carries at its outer end a cap 29 whereby the screw-barrel can be turned by the fingers when necessary. The wall of the screw-barrel 26 is traversed, throughout its entire 100 thickness between the outer periphery and the axial bore 25, by a helical slot 30 through which a radial stud 31, fixed in the plunger 24 near the rear end of the latter, projects so far it is adapted to engage in any one of 105 a series of straight longitudinally-extending

guide grooves 32 (corresponding in number and relative position to the magazine-recesses 21) formed in the inner periphery of the rear section 11 of the holder; so that, 5 according as the screw-barrel 26 is rotated in one or the other direction, the plunger 24 will be caused to move forward or rearward but without revolving about its own axis.

In the example illustrated, the helical 10 slot 30 (whose effective axial length corresponds with the length of a single lead and also with the effective length of the magazine-recesses 21) is shown as having a left-hand twist, so that the plunger 24 will 15 be advanced to feed forward a lead through the sheath 16 and the bore 23 at the point of the holder, when the cap 29 is rotated clockwise relatively to the rear end of the holder. When, owing to the advance of the plunger 20 24, the lead contained in the sheath 16 has been extruded as far as the front portion 17 of the sheath, the radial stud 31 will have reached the front end of the helical slot 30, and will also have passed beyond the 25 front end of that guide-groove 32 along which it has just been advanced, so that the stud will have entered into engagement with a notch 33 in a rotatable controlling-ring 34 which is housed in a cavity 35 in the 30 inner periphery of the wall of the section 11 just in rear of the cam-disk 19 on the sheath 16. In the angular position occupied at this moment by the semi-cylindrical sheath, 16, the open side of the sheath is 35 opposite to that now empty magazine-recess 21 whence the lead just extruded was derived, and it is therefore necessary to bring the open side of the sheath 16 opposite the next magazine-recess 21 (assumed 40 to be charged) in order that a fresh lead may be transferred from the latter recess to the sheath 16. For this purpose the screw-barrel 26 requires to be rotated, in the same direction as before, through the angular interval 45 separating two adjacent magazine-recesses 21 or, what is the equivalent of this, through the angular interval separating two adjacent guide-grooves 32. The amount of such rotation is indicated and controlled 50 by means of the controlling-ring 34, which now turns as one with the plunger 24 owing to the engagement of the stud 31 with the notch 33; the controlling-ring 34, which is formed of spring metal and split so as to 55 tend to expand radially, being adapted to engage by one of its ends in a circumferential series of ratchet-recesses 36 in the wall of the cavity 35, as indicated at 37 in Fig. 3. This arrangement permits of such continued rotation of the screw-barrel 26, plunger 24, and sheath 16, after the stud 31 has reached the forward end of its travel, as is required in order both to bring the stud 31 beneath the next guide-groove 32 60 and also to bring the open side of the sheath 65

16 opposite the next magazine-recess 21; but at the same time the arrangement prevents reverse rotation of the controlling-ring 34 when the screw-barrel 26 is subsequently turned in the opposite direction for the 70 double purpose of retracting the plunger 24 from the sheath 16 in order to make way for the introduction of a fresh lead into the sheath, and also of causing the stud 31 to ascend along the next guide-groove 32. 75

As an additional means for checking the step-by-step rotation of the sheath 16, the cam-disk 19 is formed with a series of peripheral depressions 38 (Fig. 4) with which a stationary spring-tongue 39 successively engages as the cam-disk turns along with the sheath; there being as many equally-spaced depressions 38 as there are magazine-recesses 21. The spring-tongue 39 is shown as stamped-up from a ring 40 of 80 thin sheet metal fixed within the front end of the section 11 of the holder around the cam-disk 19. 85

After the complete extrusion of a lead from the sheath 16 and the subsequent rotation of the sheath to the next angular position in the manner above described, the screw-barrel 26 is rotated in the reverse direction so as to retract the plunger 24, the radial stud 31 meanwhile sliding up the next 90 guide-groove 32. When the plunger 24 has been completely retracted, a spare lead can be shaken or allowed to fall from the magazine into position within the sheath 16, whereupon a fresh reversal of the rotation 95 of the screw-barrel 26 will bring about the extrusion of the new lead, and so on for all the leads contained in the magazine. 100

It will be evident that if the number of 105 spare leads accommodated in the magazine be materially greater than four (as shown in the example illustrated), the thickness of the tube 16 will have to be increased so as to retain such greater number of leads in their respective magazine recesses 21 until 110 the open side of the tube is brought into position opposite a spare lead which is to be allowed to drop into the tube. In such case the tube 16 will no longer be strictly semi-cylindrical, but will as indicated in Fig. 6, 115 assume the form of a solid cylinder 41 bored axially to receive a lead and having in its wall a longitudinal gap 42 (of the same width as the axial bore) adapted to allow a spare lead to pass from the magazine into 120 the bore.

What I claim is:—

1. A magazine pencil holder, comprising an outer casing, a sheath, axially of said casing, for containing that lead which is in use, 125 said sheath being provided with a longitudinal opening through which leads are introduced from the magazine; a magazine integral with said casing and surrounding said sheath, said magazine including a plu- 130

- rality of separate compartments extending longitudinally in parallel relation to said sheath, each compartment adapted to hold a single lead, means permitting step by step 5 relative rotation of said sheath and magazine in one direction only, to bring the sheath opening in register with said compartments in succession, a screw propelled plunger for advancing a lead in the sheath 10 and means controlled by said plunger for preventing relative rotation of said sheath and magazine until said screw propelled plunger has extruded the lead in the sheath a predetermined amount.
- 15 2. A magazine pencil holder comprising a casing, a plurality of longitudinally extending ribs forming magazine compartments in said casing, each adapted to hold a single lead, a sheath located centrally of said magazine compartments, said sheath being provided with a longitudinal opening adapted to be brought into register with said magazine compartments in succession by rotation of said sheath in one direction only, and 20 25 means for preventing reverse rotation of said sheath.
3. A magazine pencil holder comprising a casing, provided with a plurality of magazine compartments, each adapted for holding a single lead, a rotatable sheath located centrally of said casing and provided with a longitudinally extending opening, adapted to be brought into register with said compartments in succession for transferring 30 35 lead from a compartment to the sheath, means for preventing rotation of said sheath in one direction, a detent for locating the opening in said sheath in proper register with a compartment, screw propelled means 40 for advancing a lead in said sheath, and coöperating between the sheath and said screw propelled means whereby the latter may rotate said sheath in one direction when said screw propelled means has extruded the 45 lead a predetermined amount.
4. A magazine pencil holder comprising a casing, provided with a plurality of inwardly extending radial ribs, forming magazine compartments, each adapted to hold a single lead, a sheath mounted for rotation centrally of said casing and provided with a longitudinal opening adapted to be brought into register with each of said compartments in succession by rotating said sheath, 50 55 whereby leads in the compartments may be transferred to the sheath, a screw propelled plunger in said sheath for advancing a lead therein, a pin or stud connected with said plunger, and extending laterally for coöperation with one or another of a plurality of guide grooves extending longitudinally within said casing, said guide grooves corresponding in number with the compartments in said magazine and means whereby said 60 65 stud or pin may be moved out of one groove and rotated into line with the next adjacent groove simultaneously with the rotation of said sheath for registration with the adjacent magazine compartment.
5. A magazine pencil holder comprising a magazine section and a propelling screw section, said magazine section being provided with a plurality of radially extending partitions forming compartments, each of which is adapted to hold a single lead, a tubular sheath located centrally of said compartments and provided with a longitudinal opening, adapted to be brought into register with each compartment in succession for transferring lead from the compartment 70 to the central sheath, a plunger in said sheath and normally held against rotation while advancing a lead, means for preventing rotation of said sheath except by said plunger, a screw in said screw section for propelling said plunger in said sheath, means for preventing rotation of said plunger, while being advanced by said screw, and means for permitting simultaneous rotation by said screw of said sheath and the 75 80 85 plunger when the latter has been advanced a predetermined amount.
6. A magazine pencil holder comprising a casing, provided with a plurality of radially extending partitions, forming magazine 95 compartments, each adapted for holding a single lead, a central sheath for a single lead, provided with a longitudinal opening, adapted to be brought into register with said magazine compartments in succession by rotation of said sheath, a plunger in said sheath for extruding the lead, a screw in axial alinement with said plunger for advancing the same, coöperating means between said plunger and the casing for preventing rotation of the plunger when the screw is rotated for advancing the plunger, means within the casing for holding the plunger against advancement by the screw, said last named means being rotatable with 100 105 110 the plunger step by step in one direction, while holding said plunger against advance movement, means whereby said sheath is rotated simultaneously with the rotation of said plunger, a click detent for holding said plunger and sheath with the opening in said sheath in register with the magazine compartments in succession and means for preventing rotation of said plunger and sheath when said screw is rotated in the 115 120 opposite direction to retract said plunger from the sheath and thereby permit the entry of the lead from the registering magazine compartment.
7. A magazine pencil holder comprising a casing, a plurality of longitudinally extending ribs forming magazine compartments in said casing, each compartment adapted to hold a single lead, a rotatable sheath located centrally of said compartments, said sheath 125 130

being provided with a longitudinal opening adapted to register with one or another of said compartments, a screw propelled plunger in said sheath for extruding a lead therefrom, coöoperating means whereby said plunger is adapted to rotate said sheath, step by step, to bring the opening in the latter into

register with successive compartments when the lead in the sheath has been extruded a predetermined amount, and means for preventing simultaneous rotation of said plunger and sheath in one direction. 10

ANDREW VALEGGIA.
